UNITED STATES PATENT OFFICE.

ALBERT E. SCHAAF, OF TOLEDO, OHIO.

DESIGN FOR A FRAME OF RADIATORS FOR AUTOMOBILES.

No. 37,881.

Specification for Design.

Patented March 6, 1906.

Application filed September 29, 1905. Serial No. 280,721. Term of patent 7 years.

To all whom it may concern:

Be it known that I, ALBERT E. SCHAAF, a citizen of the United States, residing in the city of Toledo, in the county of Lucas, in the State of Ohio, have invented a certain new, original, and ornamental Design for a Frame of a Radiator for Automobiles, of which the following is a specification, reference being had to the accompanying drawing, forming a part hereof.

This invention consists in the ornamental

design for a frame of a radiator for automobiles, as shown in the accompanying drawing, which is a view in perspective of such a frame embodying the invention.

I claim—

The ornamental design for a frame of a radiator for automobiles as shown.

ALBERT E. SCHAAF.

In presence of—

R. I. CUMMINGS,
K. V. LAW.
